UNITED STATES PATENT OFFICE.

ADDISON S. HODGES, OF CHELSEA, MASSACHUSETTS, ASSIGNOR TO ESTHER ANN HODGES, OF SAME PLACE.

FLASK FOR MAKING SEAMLESS SASH-WEIGHTS.

SPECIFICATION forming part of Letters Patent No. 571,308, dated November 10, 1896.

Application filed November 11, 1895. Serial No. 568,649. (No model.)

To all whom it may concern:

Be it known that I, ADDISON S. HODGES, a citizen of the United States, and a resident of Chelsea, in the county of Suffolk and State of Massachusetts, have invented new and useful Improvements in Flasks for Making Seamless Sash-Weights, of which the following, taken in connection with the accompanying drawings, is a specification.

This invention relates to improvements on the patent granted to me November 12, 1889, No. 414,838, for flask for making seamless sash-weights, and it is carried out as follows, reference being had to the accompanying drawings, wherein—

Figure 1 represents a plan view of the improved flask, showing the sash-weight patterns placed in position therein and the flask partly rammed with sand and showing the bottom board removed. Fig. 2 represents a longitudinal section of the flask and the bottom board on a line passing through the longitudinal axes of the patterns *d d* when in position in the flask, the patterns being shown in elevation and the flask filled with sand. Fig. 3 represents a cross-section on the line 3 3, shown in Fig. 2. Fig. 4 represents a longitudinal section of the flask and its bottom board after being turned upside down and the moldboard removed. Fig. 5 represents a similar longitudinal section of the flask, showing the sash-patterns as withdrawn and the cores for forming the perforated heads of the sash-weights placed in positions within the flask ready for casting. Fig. 6 represents a detail top plan view of the head-molding device. Fig. 7 represents a longitudinal section on the line 7 7, shown in Fig. 6. Fig. 8 represents a cross-section on the line 8 8, shown in Fig. 6. Fig. 9 represents a detail side elevation of the device for ramming the sand in forming the head-molds. Fig. 10 represents a plan view of one of the finished seamless sash-weights, and Fig. 11 represents a side view of the same. Fig. 12 represents a longitudinal section on the line 12 12, shown in Fig. 10. Fig. 13 represents a similar longitudinal section on the line 13 13, shown in Fig. 11.

Similar letters refer to similar parts where-

ever they occur on the different parts of the drawings.

The flask is non-divided and composed of side pieces *a a*, secured at a proper distance apart by means of bars or braces *a' a'' a' a''*, 55 as shown in Figs. 1, 2, 4, and 5.

b is the moldboard, which serves as a support for the flask during the first part of the molding operation, and *c* represents the "bottom board," which is placed on top of the flask 60 during the first part of the molding operation, as shown in Figs. 2 and 3, and which, after the flask is reversed, is underneath the flask, as shown in Figs. 4 and 5, so as to serve as a support for the sand in the flask during the 65 casting operation.

b' b'' are pattern-supports secured to the moldboard *b*, said supports having on their upper sides semicircular recesses *b' b''*, adapted to receive the cylindrical sash-weight patterns 70 *d d*, which are placed in parallel rows within the flask with their tapering ends *d'* butting against opposite sides of the gate *e*, which is inserted in perforations in the sides *a a* of the flask, as shown in Figs. 1, 2, and 4. 75

The patterns *d* are made somewhat longer than the finished sash-weight, and for the purpose of regulating the length of the latter I place on the moldboard *b*, at or near the place where the head of the weight is to be produced, a removable pattern-support *b''*, having recesses on its upper side for receiving the patterns *d*. A similar removable and recessed pattern-support *b''* is placed above the support *b''*, as shown in Figs. 1, 2, 3, and 4, 85 and said pattern-supports are adjusted and held in position (according to the desired length of the weights) by means of set-screws *f' f''* going through bars *f f*, located in any of the vertical grooves *a' a''* on the inside of the 90 flask *a*, as shown in Figs. 1, 2, and 4.

The above-described flask is substantially like that shown and described in my aforesaid patent, No. 414,838, and I do not claim such construction and arrangement as my 95 present invention.

In Figs. 10, 11, 12, and 13, *D* represents one of the finished seamless sash-weights, having its lower end *D'* tapered as usual.

D'' is the head or upper end of the sash- 100

weight, having a lateral perforation D^3 going completely through the head from one side to the other and communicating with the conical or tapering end perforation D^4 , by which arrangement the sash-weight is rendered equally useful for attaching to it a cord, chain, or tape, as may be desired.

D^5 in Figs. 10 and 12 represents raised or recessed marks or figures on the head D'' for the purpose of indicating the weight, size, or number of the weights, as usual.

The head-molding device is fully shown in Figs. 6, 7, and 8, and it consists of a series of head-patterns $G G$, secured at distances apart equal to the distances between the respective patterns $d d$ in the flask a . The said head-patterns $G G$ are secured to a bottom board G' , upon which is loosely placed and properly guided a hollow rectangular frame H , to the under side of which is secured a perforated sand-lifter plate h , having perforations h' , through which the head-patterns G may pass easily. Within the said lifter-frame H is located the removable head-mold frame I , having lateral divisions $i i$ between the head-patterns $G G$, as shown. The said frame I is open from top to bottom and has its lower edge resting loosely on the upper side of the sand-lifter plate h , as shown.

The bottom plate G' has a longitudinal groove, in which is arranged the adjustable bar K , to the upper side of which are secured a series of mark-patterns k , adapted to be moved out of the way into recesses $g g$ in the body of the head-patterns $G G$ when the frame I and the sand within it is withdrawn from said head-patterns after the sand-molds have been made.

For the purpose of ramming the sand in the spaces inclosed between the interior of the frame I and the head-patterns $G G$, I prefer to use a ramming-tool, as shown in Fig. 9, consisting of a plate L , having attached to its under side a series of cylindrical tubes l , provided with cut-away portions $l' l''$ at their lower ends to enable the sand to be rammed into the frame I around the head-patterns $G G$ and their projecting core-prints $G'' G''$. (Shown in Figs. 6 and 8.) After the sand has been properly rammed into the spaces between the head-patterns $G G$ and the interior of the frame I it is struck off even with the top edge of the latter. The bar K , with its mark-patterns $k k$, is then moved in the direction of the arrow shown in Fig. 7, causing said mark-patterns $k k$ to enter the recesses $g g$ in the head-patterns $G G$, thus enabling the frame I and its sand-molds to be withdrawn from the head-patterns $G G$ without disturbing the impression made in the sand by the mark-patterns $k k$.

The frame I is removed from the head-patterns by raising the frame H and its perforated bottom plate h , upon which the frame I and molded sand is supported, after which the frame I is detached from the frame H and

ready for receiving the cores for the formation of the head cavities or recesses.

$k' k''$ are catches or buttons on the opposite ends of the sliding bar K for the purpose of holding it in proper position on the board G' during the process of ramming the sand within the frame I .

By releasing the catch k' the bar K may be moved in the direction of the arrow shown in Fig. 7 preparatory to the removal of the frame I and its molded sand.

In using the improved flask for molding and casting seamless sash-weights I proceed as follows: The flask $a a$ is placed on the mold-board b , the gate-pattern e passed through the perforations in the sides of the flask, and the sash-weight patterns $d d$ laid in position, as usual, in parallel rows upon the recessed pattern-supports $b'' b'' b^5 b^5$, after which the recessed bars $b^6 b^6$ are placed on top of the pattern end supports $b^5 b^5$ and the location of such pattern end supports $b^5 b^6$ adjusted by set-screws $f' f'$ on the detachable bars $f f$, as fully shown in Figs. 1 and 2, the bottom board c , however, being removed. The operator now rams the sand in the flask, as shown in Fig. 2, and strikes it off even with the upper edge of the flask. The bottom board c is then placed on top of the flask and the whole clamped together by means of clamps $q q$ or other suitable clamping devices, as shown in Fig. 3, after which the flask is reversed to the position shown in Fig. 4 and the moldboard b removed. The sprue-pattern r is inserted and the sand rammed and tucked under the bars $a' a'' a' a''$, as shown in Fig. 4. I then draw out the center gate e and fill up the openings in the side of the flask through which said gate was originally inserted. I then draw out the patterns $d d$ toward the opposite ends of the flask and remove the guide-boards $f f$ and lift away the recessed pattern-supports $b^5 b^6$. In place of the pattern-supports $b^6 b^6$ I place the frames $I I$, containing the sand-molds and cores for the formation of the perforated heads of the sash-weights, and insert the back boards $A A$ in the grooves $a^3 a^3$ back of said frames $I I$ and ram and tuck the sand on top and bottom of said frames $I I$, as fully shown in Fig. 5. After removing the sprue-pattern r the molten metal is poured in through the sprue-hole r' , as is common in the art of casting. After being cooled the sash-weights are broken off from the metal connecting the inner tapering ends, leaving said weights in a finished seamless condition, as shown in Figs. 10, 11, 12, and 13.

What I wish to secure by Letters Patent and claim is—

1. In a device for molding sash-weights, the combination with a longitudinally-grooved bottom board G' , of a series of head-patterns G secured at equal distances apart to the bottom board and each having a laterally-extending recess formed in one side, a longitu-

5 dinally-movable bar K fitted to slide in the said groove in the bottom board, and a series of mark-patterns k secured to the movable bar K and fitted in the recesses in the head-patterns, whereby said mark-patterns may be simultaneously moved into said recesses when the patterns are withdrawn from the mold, substantially as and for the purpose set forth.

- 10 2. In a device for molding sash-weights, the combination with a longitudinally-grooved bottom board G', of a series of head-patterns G secured at equal distances apart to the bottom board and provided upon their corresponding sides with laterally-extending recesses, a longitudinally-movable bar K fitted to slide in the groove in the bottom board, a

series of mark-patterns k secured to the bar K and fitted in the recesses in the head-patterns, a frame H surrounding the head-patterns, a perforated sand-lifter plate h, fitted over the head-patterns, and a sand-receiving frame I seated on said sand-lifter plate, substantially as described and for the purpose specified.

20 25 In testimony whereof I have signed my name to this specification, in the presence of two subscribing witnesses, on this 8th day of October, A. D. 1895.

ADDISON S. HODGES.
